Patented March 11, 1851.

UNITED STATES PATENT OFFICE.

J. W. FOWLE, OF BOSTON, MASSACHUSETTS.

STEAM DRILLING-MACHINE.

Specification of Letters Patent No. 7,972, dated March 11, 1851.

To all whom it may concern:

Be it known that I, JOSEPH W. FOWLE, of Boston, in the county of Suffolk and State of Massachusetts, have invented certain new and useful Improvements in Steam Drilling Apparatus, and that the following description, taken in connection with the accompanying drawings, hereinafter referred to, forms a full and exact specification of the same, wherein I have set forth the nature and principles of my said improvements by which my invention may be distinguished from others of a similar class, together with such parts as I claim and desire to have secured to me by Letters Patent.

The figures of the accompanying plates of drawings represent my improvements.

In Plate 1, Figure 1 is a side elevation of my improved drilling apparatus. In Plate 2, Fig. 2 is a plan of the apparatus, Fig. 3 is a detail longitudinal vertical section, taken in the plane of the line A, B, Fig. 2, and Fig. 4 is a transverse vertical section taken in the plane of the line C, D, Fig. 2.

In the machines which have been recently devised for splitting and dressing stone, &c., by steam, the dressing or cutting tool has been so connected to the piston rod, as to be worked by the direct action of the steam. This feature I have incorporated in my improvements, and I have also combined with it an arrangement for supporting the engine, and the drilling tool which it drives, in a frame which may swing and be raised and lowered so as to drill in any direction and at any height, also, a mechanical provision for turning the tool and one for advancing it as the drilling progresses; and, furthermore, an improved mode of preventing the direct action of the steam, from throwing the piston, as the tool is driven forward and back, through either head of the cylinder.

E, E, E, is a horizontal frame, having proper rails F F, on which the supporting framework G, G, G, for the operating parts of the apparatus rest, and move along, the sliding or moving of the same, being effected by the rack and pinion shown at H H in Fig. 1, Pl. 1, or in any other of the well known ways for producing such movements. On the rear part of the framework G, G, G, is the steam boiler I I, the steam from which is conducted through the jointed pipe K K to the cylinder L of the en-

gine. This cylinder, with all its appendages, hereinafter referred to, and described, is supported on the rectangular frame M M, which is hung at its center, so as to swing therein, in the vertically sliding boxes or bearings N N which move up and down in the rectangular openings O, O, O, O, in the vertical part of the framework G, G, G. These boxes are suspended at the ends of the cords P, P, P, P, and are raised or lowered by means of the windlass Q Q, to which said cords pass over the several guiding pulleys R, R, R. Said windlass is provided with a ratchet wheel and pawl at S, and the sliding boxes may be confined in any desired position, by means of the nuts and screws at T, working with the confining buttons U U in a manner which will be readily understood by inspection of Fig. 1, Pl. 1, and Fig. 2, Pl. 2. The frame M M is supported, in the various diagonal positions into which it may be desired to swing it, by the sustaining rods V V which are connected to its lower end on each side, and which, at their other ends, are bent so as to fit into the holes W, W, &c., formed in the horizontal and vertical metallic plates X, X, Y, Y, Fig. 1, Pl. 1, and Fig. 2, Pl. 2.

a a is the drill shaft, having the drilling tool b properly fastened to its outer end. Said drill shaft is attached to, or connected directly with, the cross head c c of the engine, so as to be nearly an elongation, as it were, of the piston rod d d, so that the tool is driven forward by the entire power of the steam acting on the piston e, Fig. 3, Plate 2. The cross head moves forward and back on the guides f, f, f, f, in the usual way, and the drill shaft a a is arranged so as to turn in its bearings g g, as it moves backward, with the cross head, by the following combination of mechanical devices.

A diagonal rod h h is fastened to the projections i, i from the engine, as shown in Fig. 1, Pl. 1, and Figs. 2 and 3, Pl. 2. A ratchet wheel k, Figs. 2, 3 and 4, Pl. 2, is permanently fastened to the inner end of said drill shaft, as shown in said figures, and a pawl holder l l (having a proper pawl m which ingages with the teeth of said ratchet wheel) extends upward and is forked at its top, so as to embrace the diagonal rod h h, as shown in said Fig. 4, Pl. 2. As the drill shaft moves forward, the pawl m moves over the teeth of the ratchet wheel and as the shaft moves back-

ward the same pawl engages with the teeth and unerringly turns the tool so that in going forward again it strikes in a different place.

5 The danger of driving the piston through the heads of the cylinder, by reason of using the direct action of the steam, in driving the drill, is obviated, in my improvements, by a peculiar mechanical arrangement for 10 operating the rocker shaft and shifting the valve of the engine, just immediately preceding each stroke of the drill or before the piston fits close to either end of the cylinder. The rocker shaft is a bell crank having its 15 arms nearly at right angles to each other shown in Fig. 2, Pl. 2, having a proper fulcrum at *o*. At the end of one of its arms it is secured to the valve rod *p*, and at the other, it has a small pin or stud *q* which fits 20 into and is moved or operated upon by the diagonal slot *r* in the plate *s* attached to the rear of the sliding rod *t t*, which rod moves forward and back in proper guides at *u u*, attached to the engine. From each end of 25 this diagonal slot *r*, a horizontal slot or one parallel to the axis of the cylinder *L*, extends toward the front and rear of the said cylinder, as shown at *v* and *w* in Fig. 2, Pl. 2. The rod *t t* is moved forward and 30 back, by means of a stud *x* on the cross head *c c*, which, as said cross head moves forward and back, abuts against the adjustable tappets *y y* secured on said rod at proper 35 points, so as to shift the valve at the proper time, as herein above suggested. Now when the stone is soft, if the momentum which the piston has acquired, would have a tendency to carry the cross head further along than the usual length of stroke, or than 40 would be sufficient to open the valve to a proper degree, the horizontal slots at *v* and *w* (after the diagonal slot *r* has shifted the valve) only slide on the pin or stud *q* of the rocker and have no further effect upon the 45 valve.

The next thing in course to be described, is the mechanical arrangement for feeding

the engine and drill shaft forward, as the tool enters the rock. The engine and its appendages are arranged, so as to slide forward and back on the ways *a' a'*, *a' a'*, 50 Figs. 2 and 4, Pl. 2. A nut *b'* attached to the engine frame fits on and is worked by the screw shaft *c' c'*, which is arranged so as to revolve intermittently at each stroke 55 of the engine, and move the whole apparatus forward, a little each time. This shaft turns in its bearings *d' d'*, attached to the swinging frame *M M* and has a ratchet and pawl *e'* at its rear end, to retain the gain 60 which is made from time to time in the forward movement of the apparatus. A metallic inclined plane *f'* is attached to the side of the cross head *c c*, and as said cross head moves forward, this inclined plane 65 presses against the end *g'* of the pawl holder *h' h'*, and the pawl *i'*, moved with said holder, engages with the teeth of the ratchet wheel *k'* fixed on the screw shaft *c' c'*, as shown in Fig. 2, Pl. 2, and thereby 70 turns said shaft, and effects the desired feeding motion. The same end, it will be seen, may be produced, by means of a rag wheel working in a chain, attached to the two ends of the engine, said wheel being turned by 75 the screw shaft in the manner well understood by machinists.

What I claim as my invention and desire to have secured to me by Letters Patent is—

The combination of a direct action steam 80 drill in which both engine and drill are mounted on a frame which slides in a swinging frame capable of being adjusted in any required position, with the apparatus substantially as herein above described which 85 is connected with and actuated by the cross head of the engine for causing the sliding frame to move along the swinging frame toward the rock.

JOSEPH W. FOWLE.
